UNITED STATES PATENT OFFICE.

JAMES P. JOHNSON, OF EAST CLEVELAND, OHIO.

HOT-AIR FURNACE.

1,317,794.

Specification of Letters Patent.

Patented Oct. 7, 1919.

Application filed December 2, 1918. Serial No. 264,945.

To all whom it may concern:

Be it known that I, JAMES P. JOHNSON, a citizen of the United States, residing at East Cleveland, in the county of Cuyahoga and State of Ohio, have invented certain new and useful Improvements in Hot-Air Furnaces, of which the following is a specification.

This invention relates to domestic hot-air furnaces, and it has particular reference to furnaces of this class wherein natural or manufactured gas is used as a heating medium.

The primary object of the present invention is to provide means for economizing in fuel, or increasing the heat efficiency of the furnace.

A further object of the invention is the provision of simple and effective means for the purpose above set forth, that can readily be installed in gas furnaces of the common universal construction, without any change or alteration in the arrangement or construction of the parts that are already embodied in the furnace structure.

As the improvement is only applicable where gas is employed, a further object is to provide means for effectively carrying out the purpose set forth, and that can readily be removed from the furnace when it is desired to use coal as the heating medium.

With these objects in view the invention consists in the novel construction and arrangement of the parts of an auxiliary element and its coöperative combination with other elements of the furnace, as set forth in the following description and definitely pointed out in the appended claims, reference being had to the accompanying drawings which are made a part of the specification and in which similar characters of reference are employed to designate corresponding parts.

In the said drawings Figure 1 is an elevation of a hot-air furnace embodying the invention, partially in central vertical section. Fig. 2 is a section on line 2—2, Fig. 1. Fig. 3 is a fragmentary plan view of the auxiliary member, on an enlarged scale, and Fig. 4 illustrates a fragment in perspective illustrating a different connecting means that will hereinafter be described.

Referring now to the drawings, Figs. 1 and 2 illustrate substantially a well known

construction of hot-air furnaces in common domestic use, with the improvement associated therewith.

The casing 1 incloses a fire-pot 2 provided with a dome 3 and a grate 4. Connections 5 are provided for conducting fuel gas from the source of supply, through mixers 6 to the fire-pot 2. The connections 5 communicate with a conduit 7 located in the wall of the fire-pot and provided with a plurality of apertures or jets 8 that open into the combustion chamber 9. When gas is used as a heating medium the fuel is ignited at the jets 8, thereby heating the fire-pot 2 and dome 3, and imparting heat to the surrounding confined air. When coal is employed, the gas supply is cut off and the coal is placed in the fire-pot on top of the grate 4. The heat generated by the burning of the coal produces the same result as that set forth in connection with gas burners.

The above brief description is applicable to the operation of hot-air furnaces heretofore in common use and therefore the construction so far described is old in the art.

As hereinbefore stated, the present invention provides for increasing the efficiency of the furnace and is applicable to hot-air furnace construction in general, as will readily be seen from the following description of the improvement and its association with the other elements of the furnace structure.

In the embodiment as illustrated, a cylindrical drum or shell 10, preferably made of sheet metal, provides a support for an exterior covering of sheet asbestos 11, which is riveted thereto. The covering provides a base for attachment by suitable adhesive, such as asbestos glue, of a layer of fibrous, fluffy or soft loose asbestos 12.

The diameter of the combined members 10, 11 and 12 is somewhat less than the interior diameter of the fire-pot 2, as best shown in Fig. 1, and for convenience of installation the shell 10 with its attached elements is made in segmental sections, means being provided for connecting the several segments to form the complete cylindrical shell. As shown in Figs. 1, 2 and 3, the segmental members 10 are provided with inturned registering ears 10^a which are connected by bolts 10^b. By making the improved device in sections it can easily be inserted through the door of the furnace and

assembled within the fire-pot, and as readily removed when it is desired to use coal for fuel.

Fig. 4 illustrates a different connecting means, wherein a clip 10^c is pivoted to an ear 10^d of one segment, and is adapted to engage an ear 10^e provided on an adjacent segment.

The improvement, fabricated as above described, is installed in the furnace, resting on the grate 4, within and concentric to the fire-pot 2, the fluffy fibrous layer 12 facing the inner wall of said fire-pot. The ignited gas through the jets 8 penetrates the fibrous non-inflammable material 12. Owing to the fluffy fibrous consistency of member 12 it is quickly heated or brought to a glowing condition, which enhances the combustion, intensifies the heat and increases the radiation, thereby producing a greater amount of heat in proportion to the fuel consumed.

The glow of the member 12 provides for the combustion, or maintenance of ignition at the jets 8 when the gas is turned low or the pressure reduced. This is a very desirable function of the invention, as in the ordinary furnace, when the gas is turned low the ignition is liable to cease and the gas unburned escapes through the furnace.

It has been demonstrated from actual practice, extending over a considerable period of time, with the improvement installed in a domestic hot-air coal furnace, that a given required amount of heat can be obtained at a saving of more than one-half of the fuel consumed, when compared with a similar furnace not equipped with the improved device.

While I have shown and described a simple practical construction of the improvement, it will be understood that there may be changes and alterations in the details of construction and in the material specified, without departing from the nature

of the invention, the limitation being governed by the scope of the appended claims.

What I claim and desire to secure by Letters Patent is:

1. In a hot-air furnace, a fire-pot provided with gas jets on the interior thereof, a grate, a hollow cylindrical shell adapted to rest on the grate in the interior of the fire-pot, spaced from the wall of said fire-pot and extending vertically therein, and a coating of non-inflammable loose fibrous material attached to the exterior of the cylindrical shell. 50

2. In a hot-air furnace, a fire-pot provided with gas jets on the interior thereof, a cylindrical shell adapted to the interior of the fire-pot, spaced from the wall of said fire-pot and extending vertically therein, said shell being in segmental sections having a non-inflammable fluffy fibrous covering on the exterior thereof, and means for connecting the several segmental sections. 60

3. In a hot-air furnace, the combination of a fire-pot provided with gas jets on the interior thereof; a shell within said fire-pot, spaced from the wall thereof, and extending vertically therein; and a non-inflammable fluffy fibrous coating attached to the exterior of said shell. 70

4. In a hot-air furnace, a fire-pot provided with gas jets on the interior thereof, a metal cylindrical shell adapted to the interior of the fire-pot, spaced from the wall of said fire-pot and extending vertically therein, said shell comprising a series of segmental sections having a coating of asbestos glue attached to the exterior thereof and a coating of loose fibrous non-inflammable material attached to the exterior of the first coating, and means for connecting the several segmental sections. 75

In testimony whereof I affix my signature.

JAMES P. JOHNSON.
